COMBINED BELL, RATTLE, AND FORK OR
SIMILAR ARTICLE

Ralph S. Gordon, New York, N. Y.

Application January 3, 1958, Serial No. 49,118

Term of patent 3½ years

(Cl. D54—12)

Fig. 1 is a plan view of a combined bell rattle and fork or similar article showing my new design.

Fig. 2 is an edge view thereof.

The essential features of my design reside in the portion shown in full lines on the drawing.

I claim:

The ornamental design for a combined bell rattle and fork or similar article, substantially as shown and described.
